UNITED STATES PATENT OFFICE.

WILLIAM A. E. HENRICI, OF BOSTON, MASSACHUSETTS, ASSIGNOR TO HENRICI
WASHING MACHINE COMPANY, A CORPORATION OF MASSACHUSETTS.

WASHING, DISINFECTING, AND DYEING MACHINE.

1,309,411.

Specification of Letters Patent.

Patented July 8, 1919.

Application filed June 26, 1916. Serial No. 105,917.

To all whom it may concern:

Be it known that I, WILLIAM A. E. HENRICI, a citizen of the United States, residing at Boston, in the county of Suffolk and State of Massachusetts, have invented new and useful Improvements in Washing, Disinfecting, and Dyeing Machines, of which the following is a specification, reference being had to the accompanying drawings, forming part thereof.

This invention has reference to improvements in machines adapted for use in washing, disinfecting, dyeing, rinsing, drying or otherwise treating fabric, material or articles by the application thereto or the withdrawal therefrom of water or other fluid with or without the use of chemicals.

One object of the invention is to provide a mechanism of the nature of a washing machine in which the work (fabric, material or articles) may be given a movement with relation to fluid without unduly entangling portions of the work.

Another object of the invention is to so construct a washing machine or similar machine adapted to alternately exert centrifugal action on its contents and to permit gravity to overcome said centrifugal action that said machine may be readily charged and discharged.

Another object of the invention is to construct a washing or similar machine having a container defining a path of travel for the work and operable to effect movement of said work that variations in the treatment of the work can be accomplished mechanically or chemically while the machine is in operation.

Still another object of this invention is to improve washing and similar machines with respect to supplying to such machines and withdrawing therefrom water, air or other fluid; and soap, bluing or other dyestuffs or chemicals, at or differing from atmospheric temperature.

Another object of the invention is to improve the construction of the container and particularly with respect to the end members of the same.

Other objects of the invention will appear from the following description.

The invention consists in the novel receptacle for the work.

The invention also consists in the novel

manner in which said receptacle is mounted and operated.

The invention also consists in the means for supplying said receptacle with water, steam, air or other fluid or liquid material.

The invention also consists in the means for discharging a portion or the whole contents of said receptacle.

The invention also consists in such other novel features of construction and combination of parts as shall hereinafter be more fully described and pointed out in the claims.

Figure 1, represents a front elevation of the improved machine.

Fig. 2, represents a side elevation of the same.

Fig. 3, represents a sectional detail view of some of the parts.

Fig. 4, represents a sectional view taken on line 4—4 Fig. 1, looking in the direction indicated by the arrows of said line.

Fig. 5, represents a similar view taken on line 5—5 Fig. 4.

Fig. 6, represents a sectional view taken on line 6—6 Fig. 1, looking in the direction indicated by the arrows of said line.

Fig. 7, represents a similar view taken on line 7—7 Fig. 6.

Fig. 8, represents a sectional view taken on line 8—8 Fig. 3.

Similar characters of reference designate corresponding parts throughout.

As shown in the drawings in its preferred form 10 indicates a substantial base having the standards or frames 11 and 12 having respectively the bearings 13 and 14 in which are journaled the shafts or trunnions 15 and 16 carrying the split collar or frame 17 having tightening devices comprising the bolts 18, 18 provided with comparatively heavy springs 19, 19. Shaft 15 has the gear 20 which is adapted to be driven by the worm shaft 21 when operated by any suitable driving mechanism or, for the purposes to be hereinafter described, by the hand wheel 22 on the shaft 21. The shaft or trunnion 16 is 100 tubular as shown in Fig. 3 and extends through the bearing 14 a suitable distance to receive various device coöperating therewith to be described.

Collar or frame 17 sustains the work receptacle or cylinder 23 which is of a length greater than the diameter of said collar 17 and has in its wall, at that side against the

shaft 16, the series of perforations 24, 24, Fig. 3, which communicate with the bore of the funnel member 25 located and secured in a compartment of suitable shape of said 5 collar 17 and having the neck 26 which extends into the bore of shaft 16.

Cylinder 23 has in its wall a series of comparatively small inspection openings closed or covered by pieces of translucent or 10 transparent material 27, 27 protected or secured in place by suitable frames. At one end of said cylinder or receptacle 23 is mounted the head 28 concave at its inner portion and having the studs or projections 15 29, 29 and the diametrical channel 30 leading to the centrally disposed valved outlet pipe 31. The charging end of such cylinder 17 has the frame 32 furnished with the series of pivoted bolts 33, 33 having nuts 34, 34 and adapted to be received in radial slots at the periphery of the closure head 35 which is hinged to said frame 32. The inner portion of this closure head 35 is substantially convex and has the series of studs 25 or projections 36, 36. The purpose of the bolts 33, 33 and their nuts 34, 34 is to effectually secure the head 35 in place to prevent leakage and any well known packing devices adapted to coöperate with such closure for 30 the purpose of making a water tight joint may be used.

At the respective ends of cylinder 23 the wall thereof has groups of perforations 37 and 38 which respectively communicate with 35 the outlets 39 and 40 having pipes 41 and 42 which in turn communicate with the bore of shaft 16. These pipes 41 and 42 have valve chambers 43 and 44 of which the valves are automatically operated by their respective 40 weighted arms 45 and 46 whereby when the free ends of said arms 45 and 46 swing toward the ends of said cylinder 23 said valves are caused to open to permit passage of fluid through their pipes 41 and 42 as the case 45 may be but, when said valve arms 45 and 46 are swung toward collar 17 said valves are caused to close. The purpose of these automatically controlled valves is at times to effect the opening of an outlet from each 50 end of cylinder 23 during the swinging movement of such end of the cylinder for a portion of the distance below the axis on which said cylinder swings or at a time when the water or other fluid in the cylinder 55 is in position to enter the particular outlet 39 or 40.

Referring now more particularly to the construction of the tubular or sleeve shaft 16 and parts related to or coöoperating therewith, as shown in Fig. 3, it will be seen that such tubular shaft 16, at its outer end, is rotatably received by the stuffing box bearing 47 of the casing 48 which latter is sustained by the bracket 49 extending from the exterior of the bearing 47. This casing 48 has

the chamber 50 which communicates with the bore of shaft 16 and has also the stuffing box bearing 51 which rotatably receives the pipe 52 having the spider frame 53 the arms of which are received by the bore of said 70 shaft 16, pipe 52 being connected by pipe 54 with the neck 26 of funnel member 25. Casing 48 has also the vent 55, and the outlet 56 while the casing of bearing 51 has the branch fitting 57 which has the main bore 75 58 and the branch bores 59, 60, 61 and 62. The wall of this fitting 57 has also the suitable vacuum valve 63, and the pressure gage pipe 64 all of which communicate with the main bore 58. Branch 59 connects with the 80 valve controlled water supply pipe 65 from the measuring tank 66 which latter has the valve controlled water supply pipe 67 whereby water of suitable temperature or steam may be supplied to said measuring 85 tank 66. Branch bore 60 is connected with the pressure pump 68 by means of pipe 69. Branch bore 61, of said fitting 57, connects with the steam supply pipe 70, which latter has the branch pipe 71 furnished with a 90 suitable safety valve 72. Branch bore 62, of said fitting 57, connects by the valve controlled pipe 73 with the tank or receptacle 74 adapted to receive from time to time suitable quantities of liquid soap, bluing, dye 95 or other material of a chemical nature. Steam is supplied to this tank or receptacle 74 through the steam pipe 75 which pipe also connects with the condenser nozzle 76 of the main waste or outlet pipe 77, 78 which 100 has the valve 79 and communicates with the outlet 56 of casing 48.

In some cases I prefer to connect the main outlet pipe 77, 78 with the casing 80 of a suction pump of ordinary construction but 105 usually I have found such pump to be unnecessary.

In the operation of the machine to wash clothing, material or articles cylinder 23, preferably empty, is caused to swing by operating the hand wheel 22, worm 21 and gear 20 until the end of said cylinder 23 having the closure head 35 is brought to a convenient position, preferably somewhat above the axis on which said cylinder 110 115 swings. The nuts 34, 34 are unscrewed on their bolts 33, 33 sufficiently to permit said bolts to be swung out of the slots in the periphery of head 35 and said head 35 is then swung on its hinges to the open position. 120 The clothing, material or articles to be washed or treated are then placed in the cylinder and the head 35 is swung to the closed position and secured by means of the bolts 33, 33 and their nuts 34, 34 as will be apparent. The load or charge of dry material to be operated on will be such as to occupy about one half the length of the cylinder 23, more or less; as a matter of fact the dry material may extend from end to end of the 130

cylinder as such dry material will consolidate somewhat when fluid is supplied. Steam under pressure is now, preferably, admitted to cylinder 23 from pipe 70 through 5 the bore of fitting 57 and pipe 52, 54. By means of such steam the work in the cylinder is sterilized and disinfected.

The valve of pipe 65 is now operated and kept open to permit a measured quantity of 10 water, of suitable temperature to pass from tank 66 through said pipe 65 and the bore of fitting 57 to pipe 52 and thence through pipe 54, member 25, 26 and the perforations 24 into cylinder 23. At this time the valve of 15 vent pipe 55 is usually opened to allow air to escape. Steam may in like manner be supplied through the pipe 70 and a suitable or desired quantity of liquid soap or material may be supplied from tank 74 through 20 pipe 73 to and through fitting 57. The various valves of said supply pipes are then preferably closed.

The mechanical manipulation of the material in the cylinder 23 can be effected by 25 causing said cylinder to oscillate or rotate on its axis. I prefer to cause said cylinder to rotate at the rate, approximately, of sixteen to eighteen rotations per minute but this will depend somewhat upon the nature 30 of the material to be operated on and the nature of the foreign matter to be removed or washed from the material. In the comparatively slow rotation of the cylinder 23 the contents of said cylinder, particularly 35 the saturated fabric, will be alternately raised by the end of the cylinder in which it is contained, assisted by centrifugal action, and dropped through the path defined by the wall of the cylinder whereby the fabric and a large portion of the liquid will 40 pass back and forth between the heads 28 and 35 of said cylinder 23, the downward movement of the work under gravity being suddenly arrested whereby said heads will 45 act as dashers against which the liquid will strike with a rebounding action which will result in forcing the liquid through the fabric. The circulation of the liquid will be assisted by the clearances between the studs or 50 projections 29 and 36 of the respective heads 28 and 35.

After a suitable length of operation on the work as just above described, determined by inspection of the work through the transparent members 27 of the cylinder 23 or by 55 time, valve 79 of waste pipe 78 is opened. Ordinarily the action of the ejector 76 will be sufficient to create a vacuum sufficient to draw off water from the lowest point in cylinder 23 through one of the pipes 41 or 42 as the case may be, through the bore of shaft 16, chamber 50 and outlet 56 to said pipe 78. 60 As it is usually desirable to draw off the liquid of one operation while the cylinder 23 65 still continues to rotate I have arranged the

valves 45 and 46 of the respective pipes 41 and 42 to open automatically as the corresponding end of cylinder 23 swings through its lower arc and automatically to close during the swinging of such end of said cylinder through its upper arc. The result of such automatic operation of valves 45 and 46 is that passages are open to water from the ends of the cylinder while water is present adjacent the outlets 39 and 40 of said cylinder while passage to air from the other end of said cylinder is closed.

If it is found desirable or necessary pump 80 may be operated to assist in drawing water from said cylinder 23 and also air 80 may be pumped into said cylinder by pump 68 through pipe 69, fitting 57 and pipe 52.

During the operation of washing above described after the soapy or detergent material from tank 74 has been supplied to the 85 cylinder it is preferred to supply steam to said tank 74 to cleanse the same, the matter washed therefrom passing ultimately into the cylinder. By this operation tank 74 is prepared from time to time to receive various chemicals adapted to be supplied to the cylinder.

After the first washing operation and while the cylinder 23 continues to rotate a second supply of liquid, and chemical, may 95 be supplied thereto and the material in the cylinder may be subjected to a second washing operation. Ordinarily, with this machine, a single washing operation followed by a series of rinsing operations with comparatively clear water will be sufficient. Such rinsing operations usually will be followed by a bluing operation in which bluing chemical supplied to the tank 74 will pass through the connecting pipes to cylinder 23 105 and a measured quantity of water will be supplied from the measuring tank 66.

As one of the operations, after the greater portion of water has passed from cylinder 23, and while said cylinder continues to rotate, steam and air, either or both may be supplied to the cylinder through the respective pipes 69, 70 and pump 80 may be operated so that during the alternate lifting and falling of the material under operation it 110 may be subjected to the action of steam or of air which steam or air, with the moisture acquired thereby from the material, is drawn off.

When it is desired to remove the material 115 from the machine cylinder 23 is brought to a stop with its end having closure head 35 downward, nuts 34, 34 of bolts 33, 33 are released and said head 35 is swung to an open position whereby the contents of cylinder 23 120 are delivered as from a chute and may be received in a suitable receptacle.

One of the great advantages of this improved machine is that clothing washed therein is not damaged by knotting together 130

and having to be forcibly separated. This is accomplished to some extent by the use of the cylinder as a longitudinal path in which the clothes are free to move back and forth 5 while being restricted in their lateral movement. The action of the clothes and water when their movement is suddenly arrested at an end of the cylinder tends to open out the clothes. This action is facilitated by the 10 fact that the inner wall of the cylinder preferably is smooth and that the length of the cylinder is at least twice its diameter so that the clothes in falling through the cylinder are prevented from spreading laterally 15 to any considerable extent.

Another advantage is that the work receives two impulses or decided actions at each complete rotation of the cylinder, that is, the work substantially at rest in one (the 20 lower) end of the cylinder will be raised by the half rotation or swinging upward of that end of the cylinder and will fall back to the other end of the cylinder and by the swinging upward of this latter end of the 25 cylinder the work will again be carried up and allowed to drop into the end of the cylinder first mentioned.

As it may be desirable to draw liquid from cylinder 23 while said cylinder is at rest 30 with the head 28 downward I have provided said head 28 with the valve controlled outlet 31.

In actual practice I have utilized this improved machine in treating yarn and fabric 35 with dystuffs and other chemicals with good results as to time of operation, economy of material and uniform coloring.

Under some conditions cylinder 23 can be divided by one or more partitions 23', see

Figs. 5 and 7 into a multiplicity of longitudinal compartments each of which may receive its own load which is separated from the loads of the other compartments.

Having thus described my invention I claim as new and desire to secure by Letters Patent,

1. A machine for treating fabric with liquid comprising a cylinder of a length considerably greater than its width, mounted to swing on an axis transverse to the 50 length of said cylinder, outlet pipes communicating with the end portions of said cylinder, and means actuatable by gravity to control passage through said pipes.

2. A machine for treating fabric with liquid comprising a cylinder of a length considerably greater than its width, mounted to swing on an axis transverse to the 60 length of said cylinder, outlet pipes communicating with the end portions of said cylinder, and means consisting of weight actuated valves to control passage through said pipes.

3. A machine for treating fabric with liquid comprising a cylinder of a length 65 considerably greater than its width, means to rotatably support said cylinder on a transverse axis, means to continuously rotate said cylinder, the ends of said cylinder being provided with outlet passages having automatic means to close said passages to the respective ends of said cylinder, when the respective ends of said cylinder are moving in their upper arc, a waste pipe with which 70 said passages communicate, and means to 75 produce suction in said passages.

WILLIAM A. E. HENRICI.
